BEE COMB FOUNDATION

Henry C. Dadant and Roy A. Grout,
Hamilton, Ill.

Application January 30, 1940, Serial No. 316,424

5 Claims. (Cl. 6—10)

This invention relates to improvements in bee comb foundations, its particular purpose being to improve the comb foundation sheet itself, so that comb sheets made in accordance with the invention can be marketed independently of the customary wooden frame so as to be bought by the beekeeper and inserted in such frames as he has. In other words, the wax comb sheets are so made that they will withstand handling independently of a supporting frame during the processes of packaging, shipping and distribution, in readiness to be installed in comb frames either newly bought for the purpose or had on hand after the removal of a previously deposited quantity of honey comb.

The prevailing practice up to the present time is to make and sell wax comb sheets which the beekeeper is required to reinforce upon fitting them in their comb frames. Minor efforts have been made at reinforcement in loosely sold wax comb sheets, and it is the ineffectiveness of these efforts that is sought to be overcome herein. Another difficulty sought to be overcome is that of the necessity of the beekeeper to purchase frames having reinforcing wires embodied therein for the reception of the previously mentioned loose wax comb sheets.

In an instance such as the last it is necessary for the beekeeper to embed the wires of the comb frame in the wax sheet, usually by heating the wires. It can readily be understood that the expense and loss of time involved in buying reinforced frames and then superimposing the heated wires thereof upon the wax comb sheets so as to embed them or by using a cold spur wheel for that purpose are factors from which this industry would welcome a relief. This is true from the additional standpoint of the hand method of installing the wires often resulting in a poor positioning of the comb foundation.

Supporting wires installed in a frame by hand are rarely stretched evenly and securely and positioned in the central plane of the comb frame. Obviously when a loose wax comb sheet is impressed upon such a wire foundation it is subject to becoming loose or slack, thus allowing the comb to slip, warp, bulge, sag or wave out of the central plane of the comb frame. With this preamble in mind the objects of the invention are as follow:

First, to provide a wax comb sheet which is so constructed as to withstand all necessary handling in packaging, shipment and distribution, and will be ready for installation in a comb frame by virtually any beekeeper.

Second, to provide a wax comb sheet which can readily be installed in a comb frame, and thereupon to afford the reasonable assurance of its occupancy of the central plane of the frame in a perfectly flat manner and even tension throughout.

Third, to embody one or more anchoring bars in a comb foundation sheet for the chief purpose of reinforcing one or more edges of the sheet and at the same time providing an anchorage for the ends of such wires combined in the comb sheet as will adapt themselves to termination at said reinforcement.

Fourth, to bind at least one edge of a comb foundation sheet with a stiffening strip that is folded over said edge and clamped down both upon the comb sheet and the ends of supporting wires embodied in the sheet, said strip serving both as an anchorage for the sheet and wires individually and as an anchorage for the sheet and wire assemblage in respect to the frame.

Fifth, to provide a combination of wires and anchoring bars respectively embodied in the body of the wax sheet and clamped onto the edges of the sheet over the ends of the wires, collectively to provide means for fastening and holding said sheet in the central plane of the comb frame, also to prevent sagging, warping, bulging or waviness of the resulting comb.

Other objects and advantages will appear in the following specification, reference being made to the additional drawings, in which:

Figure 1 is a partially sectional and elevational view of one form of the invention wherein the ends of the anchoring bar are extended for anchorage in the slot of the side bar.

Figure 2 is a side elevation of a comb frame and sheet embodying a modified form wherein the side edges of the sheet are reinforced with anchoring bars.

Figure 3 is a side elevation of a comb frame illustrating another form wherein the wax sheet has reinforced anchoring bars on the two side edges and the bottom edge.

Figure 4 is a vertical section taken on the line 4—4 of Figure 2.

Figure 5 is a horizontal section taken on the line 5—5 of Figure 2.

Figure 6 is a side elevation of a comb frame, parts being shown in section, illustrating still another form of the invention wherein the wax sheet is reinforced around all four edges.

Figure 7 is a vertical section taken on the line 7—7 of Figure 6.

Figure 8 is a vertical section on a line 8-8 of Figure 3.

It will be understood from a review of the foregoing forms of the invention that the improvement resides mainly in the wax sheet, but that the comb frame has been improved also thereby to coact to better advantage with some of the types of wax sheets. Generally the wax sheet embodies sets of longitudinal and transverse wires. The wax sheets are reinforced on one or more edges, the primary purpose of this reinforcement being that of anchoring the wires and thus indirectly strengthening the edges of the wax sheet.

It can also be readily understood that a wax sheet made on the basis of reinforced edges and wires embedded in the wax is not necessarily predicated on the right angular relationship or crossed form of longitudinal and transverse wires. These wires can be embedded in the wax according to any one of a multitude of designs. Therefore, the particular arrangement of longitudinal and transverse wires is herein intended merely as being illustrative and not a limitation to this special arrangement. Reference is now made to the drawings.

In the figures the comb frame 1 is made according to a more or less conventional plan. It comprises the top bar 2 from which the side bars 3 depend, said side bars being spaced in from the ends 4 of the top bar 2 so as to convert said ends into projections which are employed in supporting the comb frame in a beehive body or super. The lower end of each side bar 3 is slotted or notched at 5 to contain the ends of a slotted bottom bar 6. This bottom bar is either longitudinally grooved or made of two members which are secured in the notch 5 in spaced apart relationship to define the slot 7.

The wax sheet is embossed at 9 throughout its entire extent with multi-sided depressions which constitute the beginnings of honey cells. This is common structure in this art and does not need to be enlarged upon. Said wax sheet is improved by initially embedding a system of wires in it, the resulting sheet being marketed in this reinforced form in readiness for emplacement in the comb frame 1.

The wires 10 extend longitudinally of the sheet 8 and may either be smooth or straight as shown or provided with corrugations, crinkles or the like as in the instance of the transverse wires 11.

Preparatory to emplacing the sheet 8 in the frame 1 said sheet is manipulated in order to introduce the top of the sheet into a commonly existing rabbet 20 on the underside of the top bar 2, the top hooks 17 then being positioned as shown (Fig. 8). A strip 21 is then secured in the rabbet by means of nails 22. The nails are desirably driven on a pitch and in doing so the top of the sheet 8 is forced into the corner of the rabbet 20. This act exercises a pull on the transverse wires 11 so that the latter are stretched with noticeable tightness. It is also desirable and usually necessary to first drive a nail 23 into the bottom bar 6 thus to close a considerable portion of the slot 7 in the central zone of the bottom bar. This insures the retention of the bottom ends of the wires 11 when the nails 22 are later driven.

In every instance the anchoring bar is closed in upon an edge of the wax sheet 8 so that it becomes tightly clamped in place. The fragile nature of the wax of which the sheet 8 is com-

posed makes it impracticable to clamp the bar 29 solely upon the edge of the wax.

In other words, if it were undertaken to reinforce any given edge of the wax sheet 8 by clamping a bent metal strip thereto, the intended purpose would be defeated by the prompt breaking away of the strip because of the wax not being strong enough to sustain it under ordinary methods of handling and assemblage. In short, the wax would be weakened, if not torn away from the reinforcing strip, unless great care was exercised in handling, packing for shipment and during assembling in comb frames.

But this contingency will not happen because the clamping is done onto the ends of the incorporated reinforcing wires. For example, the anchoring bar 29 is clamped onto the ends of the transverse wires 11. Since the clamping is done by an instrument which takes in the full length of the bar 29 it follows that the clamping pressure is greatest at the points where the wire ends occur. Obviously the wax fills in the anchoring bar 29 at places between these points, but there is not sufficient pressure against the wax to encourage tearing.

In Figure 1 the anchoring bar 29 provides an anchorage in another sense of the word. Its ends are now extended at 31 so as to hook under the contiguous side bars 3 in the notch or slot 5. The sheet is manipulated to first position extensions 31 as shown, whereupon the top edge of the sheet is fitted in the rabbet 20. The top ends of the wires 11 are hooked, and when the strip 21 is nailed down tight by means of nails 22 the shoulders of the hooks are driven into the corner of the rabbet so as to stretch the sheet.

As an alternative to this plan of assemblage the procedure may be reversed by first driving nails through the slotted bottom bar 6 and the anchoring bar 29 situated therein. This will secure the bottom edge of the wax sheet 8. The strip 21 is next nailed in place in the rabbet 20 and against the hooks 17 or their equivalents, thereby stretching the transverse wires from bottom to top.

Figure 2 will be recognized as the first variation from Figure 1 in that anchoring bars are used to reinforce the side edges of the sheet 8 instead of a bottom edge. These anchoring bars are denoted 32 (Figs. 2, 4 and 5), and when they are clamped down upon the edges of the wax sheet the greatest pressure is exerted upon the ends of the longitudinal wires 10 which are thus firmly gripped. The top and bottom extremities of the bars 32 are nailed in place. The top edge of the sheet 8 including the top ends of the bars 32 is emplaced in the rabbet 20 whereupon the nails 22 are driven through both the strip 21 and the top ends of said bars as shown.

The bottom end of the wax sheet hangs in the slot 7 of the bottom bar whereupon nails 33 are driven through said bottom bar and through the anchoring bars to complete a firm mounting. Actually the procedure would be to emplace the wax sheets 8 and drive the nails 22, 33 at either the right or left end. Then in driving the nails 22, 33, they can be set at a pitch so as to exercise a longitudinal pull upon the entire sheet. This stretches the wires 10 and flattens the wax out perfectly.

In Figure 3 the wax sheet 8 is bound on three sides, the two side bindings being designated 36, 37, and the bottom binding 38. The top edge is left without any binding (Fig. 8), but a firm anchorage is secured by virtue of clamping the top hooks 17 into the corner of the rabbet 20 by

means of the strip 21 and nails 22. Inasmuch as the wax sheet has anchoring bars on the three exposed edges it is readily understood that there is a rigid support for both the wax and the wires. When said sheet is secured to the top bar 2 the wax foundation is held as firmly as ever needed. The bottom edge of the sheet loosely occupies the slot 7 of the bottom bar 6, but if it is deemed desirable a nail may readily be driven through as in the instance of the nail 23.

Figure 6 illustrates a further development of the affixation of anchoring bars to the wax sheet 8. Here all four edges of the sheet are provided with metal or equivalent bindings. The anchoring bars at the top and bottom edges are denoted 39, 40, while those at the side edges are denoted 41, 42. The longitudinal and transverse wires 10, 11 are thus firmly anchored throughout. That is to say, the extremities of the wires 10 are anchored in the bars 41, 42, while the extremities of the wires 11 are anchored in the bars 39, 40. This type of comb foundation is the most rigid of all, but the additional cost which its manufacture involves would be justified by the absolute assurance that the ultimate honey comb will be adequately supported against any distortion whatsoever.

It is not so material how the type of wax sheet in Figure 6 is emplaced in the frame 1. The conventional mode of attachment involves the rabbet 20 and the nailing strip 21. This strip should be jammed over against the top bar 39 in nailing. The bottom bar 6 may comprise the slotted type, or it may simply be grooved at 43 (Fig. 7) to admit the anchoring bar 40, a loose suspension of the wax sheet resulting in either case.

The distinct advantage of longitudinal wires over vertical wires is that bees, during dry weather or a drought or whenever there is little or no nectar yielding blossoms or honeyflow, damage comb foundation sheets considerably at times by removing the wax from them and carrying it to combs that are partly or fully drawn out whenever bees are in need of some wax for comb building purposes. It is well known that when performing such damage bees are prone to remove wax along vertical wires more than they do along longitudinal ones. The reason for this is that the bottom edges of their combs in nature, as in bee trees, are ordinarily not fastened to anything. Therefore, the bottom of the comb is the last part to be completed and the first place along which they gnaw, and when a vertical wire is found there they begin to gnaw along it. This results in badly riddled combs at times along the vertical wires and upward.

Thus it is plain that the longitudinal wires must be relied upon to maintain the integrity of the wax sheet more so than transverse wires alone because the embodiment of longitudinal wires in the sheet will tend to frustrate the natural instinct of the bees to remove the wax under the circumstances recently named.

We claim:

1. A honey comb foundation comprising a

frame including a top bar and a pair of side bars, said side bars having notches, a wax sheet mounted within said frame and having a system of wires embedded therein, combined reinforcing and anchoring means along the bottom edge of the sheet, being clamped tightly upon the wires contiguous to said edge and having extensions seated in said notches for the anchorage of the bottom of the sheet, and means secured to the

10 top bar and at the same time clamping the top edge of the sheet, said means exercising a pull on the wires thus to stretch the wires and hold the anchoring means tightly in said notches.

15 2. A honey comb foundation comprising a frame including a pair of top and bottom bars, a wax sheet mounted in the frame, a set of wires embedded in the sheet and having their ends extending to the side edges of the sheet, anchoring bars fitted upon said side edges in the form of bindings, being clamped hard against the wire ends to exercise a grip, and means securing said anchoring bars at their ends to the top and bottom bars of the frame.

20 3. A honey comb foundation comprising a frame including top and bottom bars and a pair of side bars, each of the side bars having a notch, a wax sheet mounted within the frame and having a wire embedded therein, a combined reinforcing and anchoring means clamped rigidly to one edge of the sheet and having extensions seated in the notches which are located adjacent one of the first mentioned bars for securing said edge of the sheet in position, and means for securing the opposite edge of the sheet to the other of the first mentioned bars.

25 4. A honey comb foundation comprising a frame including top and bottom bars, a wax sheet mounted in the frame, at least one set of wires embedded in the wax, the ends of the wires extending to the edges of the sheet, and at least one reinforcing U-shaped bar applied to one of the sheet edges whereat the wire ends terminate, the side walls of the U-shaped bar being rigidly pressed towards each other so that the bar will be clamped upon the wire ends and the contiguous portions of the wax sheet along one edge, means securing the U-shaped bar to one of the frame bars, and means securing the opposite edge of the wax sheet to an oppositely disposed bar of the frame.

30 5. A honey comb foundation comprising a frame including a pair of top and bottom bars, a wax sheet mounted in the frame, a set of wires embedded in the sheet and having their ends extending to the edges of the sheet, anchoring bars fitted upon said side edges, and upon one end edge in the form of bindings, being clamped hard against the wire ends to exercise a grip, and means securing said side anchoring bars at one end and securing the end anchoring bar to an adjacent frame bar.

HENRY C. DADANT.
ROY A. GROUT.
